UNITED STATES PATENT OFFICE.

HENRY T. WITTICH, OF ASHTABULA, OHIO.

FASTENING DEVICE FOR VEHICLE-TOPS.

1,348,917.

Specification of Letters Patent. Patented Aug. 10, 1920.

Application filed August 31, 1918. Serial No. 252,256.

To all whom it may concern:

Be it known that I, HENRY T. WITTICH, a citizen of the United States, and a resident of Ashtabula, county of Ashtabula, 5 and State of Ohio, have invented a new and useful Improvement in Fastening Devices for Vehicle-Tops, of which the following is a specification, the principle of the invention being herein explained and the best 10 mode in which I have contemplated applying that principle, so as to distinguish it from other inventions.

The fastening device of present interest is more especially designed for attaching 15 the forward more or less horizontally extending bow of an automobile top to the windshield frame, or to the special standard rising from the vehicle body, as sometimes provided alongside the wind-shield frame 20 proper. This mode of attachment is obviously preferable to the long straps and the like which were formerly used to tie down the front ends of such tops, the object of the present invention being to provide a 25 device of the sort just described that will be simple in operation and inexpensive in its construction.

To the accomplishment of the foregoing and related ends, said invention, then, 30 consists of the means hereinafter fully described and particularly pointed out in the claims, the annexed drawing and the following description setting forth in detail certain mechanism embodying the invention, 35 such disclosed means constituting, however, but one of various forms in which the principle of the invention may be used.

In said annexed drawing:—

Figure 1 is a broken side elevation of a 40 foldable top of the kind hereinbefore referred to, shown in its extended position and partly broken away in order to illustrate my improved device in place thereon; Fig. 2 is a side elevation, on a larger scale, 45 of such device; Fig. 3 is a transverse vertical section of the same taken on the plane indicated by the line 3—3, Fig. 2; Fig. 4 is a horizontal section taken on the plane indicated by the line 4—4, Fig. 2; Fig. 5 is 50 a longitudinal vertical section of a detail, the plane of such section being indicated by the line 5—5, Fig. 4; and Fig. 6 is a view similar to Fig. 5, but showing a modification in construction.

55 The construction of the top of course is a matter of indifference so far as the opera-

tion of my improved fastening device is concerned, the one illustrated being the commercial form of so-called "one man" top characterized by having a forwardly inclined main bow 1 that is pivotally attached to the vehicle body 2 adjacent to the rear seat thereof, where such body is two seated as shown. A rearwardly inclined main bow 3 is pivotally attached to such first-named 60 main bow near the point where it is thus attached to the vehicle body, and a jointed outrigger bow 4 likewise pivotally attached to such first-named bow, extends forwardly in a more or less horizontal direction over 70 the front seat of the body in the open condition of the top illustrated in Fig. 1. An intermediate bow 5 carried by the outrigger bow serves to support the top material 6 intermediate between the forward portion or 75 outrigger bow proper and the main bow 1.

Rising from the dash or cowl 7 are two 80 posts or standards 8, which may, as in the construction illustrated, form the side members of the wind-shield frame, or be independent supports, as desired, the upper ends of these standards being so disposed as to lie just within the transverse portion 9 of the outrigger bow 4 in such open condition of the top. The upper ends of these standards are in the form of cylindrical studs 10, 85 as best shown in Figs. 4 and 5, having their upper ends reduced so as to leave a shoulder or collar 11.

Attached to the inside of the bow, so as to 90 register with each such stud, is a bracket 12 formed out of a unitary sheet metal stamping, said bracket comprising two similar parts bent back upon themselves, leaving a round aperture 13 at the outer end of the 95 bracket of the proper diameter to snugly fit around the reduced end of the corresponding stud. The inner ends of the bracket parts spread in opposite directions to bear against the face of the bow 9, to 100 which they are attached by screws or like suitable means.

Intermediate between the inner end and the outer apertured end of the bracket, the component parts of the stamping are formed 105 with longitudinally extending recesses 14, preferably formed by depressions that provide corresponding strengthening ribs 15 on the outer sides of such parts. In such recesses, one end of a flat spring 16 is securely 110 held by a rivet 17 passing through the complementary portions of the stamping

and such spring end, as shown in Figs. 3 and 4. In place of such rivet the parts in question may be spot-welded together if desired. The outer end of spring 16 is in the form of 5 an **S** with its intermediate portion lying transversely of the bracket and in position to bear against the upper end of the stud 10, slots 18 being formed in the respective sides of the bracket stamping to permit the curved 10 portions of the spring to project without the same. The face of the stud at the point where the spring thus contacts with the same is preferably recessed transversely at 19 so as to allow such spring to have interlocking 15 engagement therewith, as shown in Fig. 5, but by pressing the outer end of the spring inwardly, *i. e.*, toward the base of the bracket, the stud will be disengaged from the fastening device, and the bow 9 to which 20 the latter is attached may be tilted upwardly away from the stud.

In the modified form of construction shown in Fig. 6 the upper edge of the recess 20 thus provided in the stud for engagement 25 with the spring is beveled, so that the spring not only serves to lock the device and thus the bow 9 to the stud, but tends to pull the device downwardly until its outer end rests on the shoulder 11. Any tendency to rattle, 30 on the part of the fastening device, is thus eliminated.

The device as just described obviously constitutes a very simple manufacturing proposition, since the stamping, constituting the 35 bracket, may be made from strip stock by automatic machinery, a single operation serving to form the grooves 14 and the slots 18. To assemble the device, then, it is merely necessary to bend the two complementary 40 parts of the stamping into contact, with the spring in place, and thereupon rivet or spot-weld such parts together. Operatively, the device fulfills all requirements for a fastening 45 between a vehicle, or like top, and a support such as a wind-shield.

Other modes of applying the principle of my invention may be employed instead of the one explained, change being made as regards the mechanism herein disclosed, 50 provided the means stated by any of the fol-

lowing claims or the equivalent of such stated means be employed.

I therefore particularly point out and distinctly claim as my invention:—

1. In a device of the character described, 55 the combination of a stud, a bracket consisting of a unitary sheet-metal stamping bent upon itself and forming an opening at its outer end adapted to fit over such stud; and a spring secured at one end between the parts 60 of such stamping and bent to normally intersect such opening.

2. In a device of the character described, 65 the combination of a stud, a bracket consisting of a unitary sheet-metal stamping bent upon itself and forming an opening at its outer end adapted to fit over such stud; and an **S**-shaped spring secured at one end between the parts of such stamping and bent to normally intersect such opening. 70

3. In a device of the character described, 75 the combination of a stud formed with a transverse recess; a bracket in the form of a unitary sheet-metal stamping comprising two complementary parts bent together and forming an opening at its outer end adapted to fit over such stud, such parts being slotted adjacent such opening; and a recurved spring secured at one end between such parts and lying in the slots therein so as normally to 80 intersect such opening and engage the recess in said stud.

4. In a device of the character described, 85 the combination of a stud formed with a transverse recess; a bracket in the form of a unitary sheet-metal stamping comprising two complementary parts bent together and forming an opening at its outer end adapted to fit over such stud, such parts being slotted adjacent such opening; and a recurved spring 90 secured at one end between such parts and lying in the slots therein so as to normally intersect such opening and engage the recess in said stud, said spring and recess being formed to tend to move said bracket longitudinally of said stud, upon engagement 95 therebetween.

Signed by me, this 23rd day of August, 1918.

HENRY T. WITTICH.
